UNITED STATES PATENT OFFICE.

STEPHEN A. DAVIS, OF NEWARK, NEW JERSEY, ASSIGNOR TO THE DOMESTIC SEWING MACHINE COMPANY OF NEW JERSEY.

DESIGN FOR A PENCIL-SHARPENER.

SPECIFICATION forming part of Design No. 21,864, dated September 20, 1892.

Application filed August 26, 1892. Serial No. 444,200. Term of patent 7 years.

To all whom it may concern:

Be it known that I, STEPHEN A. DAVIS, a citizen of the United States, and a resident of Newark, Essex county, and State of New Jersey, have invented and produced a new and original Design for Pencil-Sharpener, of which the following is a specification, reference being had to the accompanying drawings, forming a part thereof.

Referring to the drawings, Figure 1 represents a side view of a pencil-sharpener, showing my design; Fig. 2, a view from the side opposite that shown in Fig. 1, and Fig. 3 a view at right angles to that shown in Fig. 2. Fig. 4 shows an end view of the same.

The leading feature of my design consists in a longitudinal circular body having a series of flat surfaces on its outer circumference.

a represents the body of the pencil-sharpener, which is somewhat greater in length

than in diameter and is circular in its general contour when viewed from one end, as shown in Fig. 4.

The outer circumference of the body *a* is 25 provided with rows of connecting flat surfaces or faces *b*, which are intersected by grooves or depressions *c*, extending in a line parallel therewith.

The body *a* has a groove *d*, formed in its 30 outer face, extending in the direction of its length in which the cutting-blade is located. This groove, however, does not form a feature of my design, which latter is fully illustrated, as shown in Fig. 1 of the drawings. 35

What I claim is—

The design for a pencil-sharpener, substantially as herein shown and described.

STEPHEN A. DAVIS.
